Des. 186,803
Patented Dec. 1, 1959

186,803

MAGAZINE RACK

John W. Skinner, South Bend, Ind.

Application November 28, 1958, Serial No. 53,573

Term of patent 7 years

(Cl. D80—9)

FIG. 3

FIG. 1

FIG. 2

Figure 1 is a front elevational view of a magazine rack embodying my new design;

Figure 2 is a left side elevational view thereof; and Figure 3 is a top plan view thereof.

I claim:

The ornamental design for a magazine rack, substantially as shown.
